(57) **CLAIM**

The ornamental design for a wearable device with graphical user interface, as shown and described.

DESCRIPTION

FIG. 1 is a front view of a wearable device with graphical user interface showing the claimed design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken lines in the figures show portions of the wearable device with graphical user interface that form no part of the claimed design.

1 Claim, 4 Drawing Sheets
